(57) **CLAIM**

The ornamental design for the snowmobile seat as shown and described.

DESCRIPTION

FIG. 1 is a left front perspective view showing the new design for a snowmobile seat;

FIG. 2 is a left side view thereof;

FIG. 3 is a right side view thereof;

FIG. 4 is a rear view thereof;

FIG. 5 is a front view thereof;

FIG. 6 is a top view thereof; and,

FIG. 7 is a bottom view thereof.

The portions of the snowmobile seat shown in broken lines form no part of the claimed design.

1 Claim, 6 Drawing Sheets
